United States Patent Office.

GUSTAVE FRANZ HEDRICH, OF BUFFALO, NEW YORK.

Letters Patent No. 63,157, dated March 26, 1867.

IMPROVED SASH-FASTENER.

The Schedule referred to in these Letters Patent and making part of the same.

TO ALL WHOM IT MAY CONCERN:

Be it known that I, GUSTAVE FRANZ HEDRICH, (formerly of Moritzburg, Saxony,) now of the city of Buffalo, in the county of Erie, State of New York, have invented a new and improved Sash-Fastener; and I do hereby declare that the following is a full and exact description thereof, reference being had to the accompanying drawings, making part of this specification, in which—

Figure 1 is a vertical section near the edge of the upper and lower sash of a window, showing my improved fastener in place in the latter.

Figure 2 is a similar enlarged section of a portion of the lower sash detached.

Figure 3 is a perspective view of the fastener detached.

Like letters of reference designate corresponding parts in all the figures.

My fastener is designed to be attached to the lower sash of a window, and is adapted to secure either sash in any desired position by locking them together; and the invention consists in the peculiar construction and arrangement of the device by which the above is accomplished, as hereafter fully set forth.

In the drawings, A represents the upper and B the lower sash.

My fastener consists of a lever or plate, C, of suitable length, pivoted at or near the centre to two side-plates, or bearings *dd*, (fig. 3,) which are fastened to the inner face of the stile of the lower sash near the top by screws, as shown. To the back side of the lever C is attached a flat spring, *e*, or, equivalent, for which is provided a mortise, *F*, in the sash, as represented, while from the upper end of the plate projects a pin or bolt, *g*, of sufficient length to extend through the lower sash, and into or under the upper one, as shown in fig. 1. *H* is a knob, provided with a dove-tail groove, *o*, in its base, which fits so as to slide over a ledge or way, *i*, of corresponding form, attached to, or forming part of, the face of the lower end of the lever C, as most clearly shown in figs. 2 and 3. At each end of the way *i* projects a small spur or pin, *s*, to prevent the knob from sliding off the former, there being a second groove, *r*, (fig. 2,) extending part way through the knob, so as to allow the latter to be slid down so that its base will partially project below the end of the plate or lever C, forming a stop to lock the device, as will presently be described. Any other construction by which the knob or finger-piece of the lever is made to slide so as to produce this result may be employed. My fastener is attached to the under sash (preferably) in such a position that, when both sashes are closed, the bolt *g* will protrude under the bottom rail of the upper sash, firmly securing both in place. The knob *H* is then slid down, if it does not fall by its own gravity, so that a portion of its base will overlap the sash B below the end of the lever C, and prevent the latter being depressed into the mortise *F*, and thereby securing the bolt *g* from being forced in by a person on the outside. When it is desired to unlock the sash for the purpose of raising the one or lowering the other, the knob *H* is slid up the way *i* to the position shown in fig. 3; then, by pressing on the same, the plate C is depressed, as shown in red lines, fig. 2, which withdraws the bolt, and allows the change to be made, when the action of the spring *e* causes the device to resume its' normal position, again locking the sash, as shown in red lines, fig. 1. By the use of my improved fastener one only is required for both sashes, as it is evident that the device, as shown, is adapted equally to lower the upper as well as raise the lower sash. It firmly secures both sashes against displacement. The adjustable knob *H* enables the device to be so locked as to prevent the sash being unloosened from the outside.

What I claim as my invention, and desire to secure by Letters Patent, is—

The improved fastener, consisting of the combination of the sliding knob *H*, or its equivalent, pivoted lever C, provided with the bolt *g* and spring *e*, arranged and operating substantially as set forth.

In witnesss whereof I have hereunto signed my name in the presence of two subscribing witnesses.

GUSTAVE FRANZ HEDRICH.
